CONTROL APPARATUS

Roy R. Stevens, Forest Hills, Pa., assignor to The Westinghouse Air Brake Company, Wilmerding, Pa., a corporation of Pennsylvania

Application March 30, 1944, Serial No. 528,677

3 Claims. (CL 121—38)

This invention relates to control apparatus and more particularly to means for controlling the speed or power output of an internal combustion engine.

In internal combustion engines, such as the Diesel type, which employ compressed air for controlling the starting of the engine and for controlling the supply of fuel to the engine, it is desirable when the engine is running, that a loss of the compressed air, due for example to rupture of a fluid pressure supply pipe, will not result in stopping of the engine, since it might be impossible to restart the engine. Further, such undesired stopping of the engine might result in a disaster which could possibly be averted if the engine did not stop, by control of the engine speed or output by auxiliary speed control means such as hand operated throttle lever on the engine.

The principal object of the invention is therefore the provision of a pneumatic speed control apparatus for an internal combustion engine which provides for adjustment of the speed and for stopping of the engine by fluid under pressure and which is so arranged as to prevent stopping of the engine in case of loss of the supply of fluid under pressure.

Other objects and advantages will be apparent from the following more detailed description of the invention.

In the accompanying drawing, Fig. 1 is a diagrammatic view, partly in section and partly in outline, of a fuel control apparatus embodying one form of the invention; and Fig. 2 is a view similar to a portion of Fig. 1 but embodying another form of the invention.

Description

As shown in Fig. 1, the reference numeral 1 indicates a rockable shaft for varying the fuel supply to an internal combustion engine and for cutting off the supply of fuel to said engine. The shaft 1 may control the supply of fuel directly by being arranged to adjust the fuel injectors on the engine, or, if desired, said shaft may control the adjustment of a speed governor arranged to control the fuel supply to the engine. The specific fuel control means controlled by the shaft 1 is immaterial to the invention.

A lever 2 is connected to shaft 1 for rocking same and this lever may have "stop," "idle" and "full speed" positions as indicated in the drawing for adjusting the shaft 1 to provide, respectively, for cutting off of the supply of fuel to the engine to stop it, to supply fuel to the engine in an

amount to allow operation of the engine at a minimum or idling speed, and to supply fuel to the engine in an amount to cause operation of the engine at a maximum speed or maximum degree of power output. Adjustment of lever 2 to any position between "idle" and "full speed" is adapted to vary the fuel supply to the engine as required to provide for operation of the engine at a corresponding speed or degree of output.

For controlling adjustment of lever 2, there are provided in the structure shown in Fig. 1, a speed control device 3 and a stop device 4, while an operator's control valve device 5 is arranged to control operation of the devices 3 and 4.

The speed control device 3 comprises a casing containing a movable member preferably in the form of a flexible diaphragm 6 having at one side a pressure chamber 7 open to a speed control pipe 8 and having at the opposite side a non-pressure chamber 9. A rod 10 is secured centrally to the diaphragm by followers 11 and 12 and a nut 13 and extends through the non-pressure chamber 9 and a suitable bore in the casing to the exterior thereof. A calibrated regulating spring 14 encircling the rod 10 within the non-pressure chamber is supported at one end on the casing, while the opposite end bears against the follower 11. The spring 14 is under pressure for urging the diaphragm 6 to the position shown in the drawing and to oppose, with increasing force, movement of said diaphragm and of rod 10 from this position to a position which may be defined by follower 11 contacting the casing.

The stop device 4 comprises a casing containing a movable member which may be in the form of a piston 16 having at one side a chamber 17 open to a control pipe 18 and having at the opposite side a non-pressure chamber 19. A rod 20 secured at one end to piston 16 projects through the non-pressure chamber 19 and a suitable bore in the casing to the exterior thereof. A spring 21 encircling rod 20 within chamber 19 is supported at one end on the casing and bears at its opposite end against piston 16. This spring 21 is under pressure for constantly urging the piston 16 in the direction for contact with an annular stop 22 provided in pressure chamber 17 and is operative to yieldably oppose movement of said piston from this position to a position arranged to be defined by contact between said piston and an annular stop shoulder 23 provided in the non-pressure chamber 19.

The piston rod 20 extends from the piston in the same direction as the rod 10 extends from the diaphragm 6, and the end of rod 20 is connected

by a pin 24 to one end of a lever 25, while the end of rod 19 is connected by a pin 26 to said lever intermediate its ends. The opposite end of lever 25 is connected by a pin 27 to one end of a link 28, while the opposite end of said link is connected by a pin 29 to the free end of the engine's speed or fuel control lever 2.

The operator's control device 5 may comprise a self-lapping valve device 30 of any suitable structure arranged to either open the control pipe 8 to atmosphere or to supply fluid from a fluid pressure supply pipe 31 to pipe 8 at any desired pressure up to a maximum degree. For the purpose of illustration, the self-lapping valve device may comprise a control plunger 32 operable in the position shown in the drawing to provide for opening of pipe 8 to atmosphere and operable upon displacement from this position into the device to supply fluid to pipe 8 at a pressure proportional to the degree of such displacement.

A cam 33 mounted to turn with a shaft 34 is provided for controlling the plunger 32, and a lever 35 is connected with shaft 34 for turning the same. The lever 35 has "stop," "idle" and "full speed" positions as indicated in the drawing and which positions it will be noted correspond to the positions of the fuel control lever 2.

The peripheral surface of cam 33 which contacts plunger 32 is so formed as to allow movement of said plunger to its outermost position shown in the drawing with the lever 35 in and between "stop" and "idle" positions, but to displace said plunger into the self-lapping valve device 30 upon movement of lever 35 from "idle" position in the direction of "full speed" position, and to permit movement of said plunger out of said device upon movement of said lever in the direction from "full speed" position to "idle" position. The cam 33 is so designed that the degree of displacement of the plunger 32 into the self-lapping valve device will vary in proportion to the distance the lever 35 is away from "idle" position, whereby the pressure of fluid effective in pipe 8 may be adjusted between atmospheric pressure provided in "idle" position of lever 35 and any degree up to a maximum which will be obtained with said lever in "full speed" position.

The operator's control device further comprises a poppet valve 36 contained in a chamber 37 and arranged to control communication between said chamber and a chamber 38. Chamber 37 is connected to the fluid pressure supply pipe 31, while chamber 38 is connected to pipe 18. A spring 39 in chamber 37 acts on the valve 36 for urging it towards its closed position, and said valve is provided with an unseating stem 40 projecting through chamber 38 and a bore in the casing into operative alignment with the peripheral surface of cam 33. Beyond that portion of cam 33 that is arranged for operating plunger 32 of the self-lapping valve device 30, there is provided a raised portion 41 for engaging the valve stem 40 to open the poppet valve 36 when the operator's control lever 35 is moved into the "stop" position. When the operator's control lever 35 is in "idle" and "full speed" position or any intermediate position, the raised portion 41 will be moved out of contact with valve stem 40 to allow closing of valve 36 by spring 39. The valve stem 40 may be provided with one or more fluid pressure release grooves 42 of such length as to connect chamber 38 to the exterior of the casing and atmosphere with the valve 36 closed. With valve 36 open the outer ends of groove 42 will be dis-

posed within the bore in the casing in which the valve stem 40 is mounted.

In operation, with the operator's control lever 35 in "stop" position, the self-lapping valve device 30 will open pipe 8 and thereby pressure chamber 7 in the speed control device 3 to atmosphere, so that spring 14 will be permitted to hold the diaphragm 11 and rod 10 in the positions shown in the drawing. Further, with the control lever 35 in "stop" position, the poppet valve 36 will be open and allow fluid under pressure to flow from the supply pipe 31 to pipe 18 and thus into pressure chamber 17 in the stop device 4, and this pressure, effective on piston 16, will move said piston and the rod 20 to the position in which it is shown in the drawing.

With the speed control rod 19 and stop device 20 both positioned as shown in the drawing, the lever 25, and link 28 will assume the positions shown in the drawing and thus position the fuel control lever 2 and shaft 1 in their "stop" positions for cutting off the supply of fuel to the engine to permit stopping thereof.

To allow the engine to be started and then run, the lever 35 may be moved from "stop" position to "idle" position and the engine may be started in conventional manner in response to such movement of said lever or by an independent maneuvering control lever, which, however is immaterial to the invention.

The movement of lever 35 from "stop" position to "idle" position, however, permits closure of the poppet valve 36 and release of fluid under pressure from pressure chamber 17 in the stop device 4 by way of the release grooves 42 in the poppet valve stem. Piston 16 in the stop device 4 is then moved by spring 21 into contact with stop shoulder 22 and this pulls the connected end of lever 25 in toward the casing to a new position.

With the operator's control lever 35 in "idle" position still opening chamber 7 in the speed control 3 to atmosphere, the parts of said device will be in the position in which they are shown in the drawing so that movement of lever 25 by the stop device 4 as just described will rock said lever about its connection with the speed control device 3 and pull the fuel control lever 2 from its "stop" or fuel cutoff position to its "idle" position to provide for supply of fuel to the engine in an amount sufficient to allow starting of the engine and operation thereof at an idling speed.

It will now be seen that this movement of the operator's control lever 35 from "stop" position to "idle" position has no effect upon the speed control device 3; it merely causes operation of the stop device 4 to move the fuel control lever 2 to its "idle" position.

At the time of starting the engine, the operator may desire to provide a greater amount of fuel to the engine than obtained in "idle" position of lever 2 and this may be accomplished by moving the lever 35 from "stop" position past "idle" position in the direction of its "full speed" position to any desired degree. Upon such operation of lever 35, the stop device 4 will operate as above described to change the position of the connected end of lever 25, and at the same time the self-lapping valve device 30 will operate to supply through pipe 8 to chamber 7 in the speed control device 3, fluid at a pressure corresponding to the position of the operator's control lever 35.

When the pressure of fluid thus provided in chamber 7 of the speed control device 3 is in-

creased sufficiently to overcome spring 14, the diaphragm will move or deflect to a position in which the increasing pressure of said spring balances the pressure of fluid. This movement of diaphragm 6 and rod 10 will rock the lever 25 about its connection with rod 28 of the stop device 4, and thus pull the fuel control lever 2 past its "idle" position in the direction of "full speed" to a position corresponding to the position of diaphragm 6 in the speed control device 3 and thus in accordance with the speed position of the operator's control lever 35. After the engine is started it will then run on fuel at a speed determined by the position of the fuel control lever 2 which corresponds to the position of the operator's control lever.

After the engine has been started and is running on fuel, the operator, by moving his control lever to "idle" position, will cause operation of the speed control device 3 to correspondingly position the fuel control lever 2. Movement of the operator's control lever 35 to "full speed" position will effect operation of the speed control device 3 to effect like positioning of the fuel control lever 2, while movement of the operator's control lever to any position intermediate "idle" and "full speed" will cause operation of the speed control device 3 to correspondingly position the fuel control lever 2, as will be apparent. It will thus be seen that with fluid under pressure released from the stop device 4, the operator by proper adjustment of lever 35 between "idle" and "full speed" may obtain operation of the engine at any desired speed.

When the operator desires to stop the engine he will move the control lever 35 to "stop" position to open chamber 7 in the speed control device 3 to atmosphere and to permit the parts of said device to return to the position in which they are shown in the drawing. This operation of lever 35 also opens the poppet valve 36 to supply fluid under pressure to the stop device 4 for causing the parts thereof to again assume the position in which they are shown in the drawing, and this operation of the stop device actuates lever 25 to positively return the fuel control lever 2 to its fuel cutoff or "stop" position for cutting off all supply of fuel to the engine to stop it.

From the above description it will now be seen that since fluid under pressure is released from the stop device 4 while the engine is running, a failure or loss of the supply of fluid under pressure through pipe 31 to the operator's control device and a consequent loss of fluid under pressure from chamber 7 in the speed control device 3, will only result in operation of the speed control device 3 to move the fuel control lever 2 to "idle" position. A loss of fluid under pressure will not therefore cause stopping of the engine. In order to stop the engine fluid under pressure is required for operating the stop device 4.

If desired, the functions of the speed control device 3 and stop device 4 may be combined in a single device, such as a speed and stop control device 45 shown in Fig. 2.

The speed and stop control device 45 comprises a casing containing a movable member 46 having at one side a pressure chamber 47 arranged to be connected to the speed control pipe 8 and having at the opposite side a non-pressure chamber 48. A rod 49 is connected centrally to diaphragm 46 by means of followers 50 and 51 and a nut 52. The casing is provided with a stop shoulder 53 for contact by follower 50 to limit deflection of diaphragm 46 in one direction, while a shoulder 54

5 is arranged for engagement by follower 50 to limit deflection of diaphragm 46 in the opposite direction by fluid under pressure supplied through pipe 8 to chamber 47. The non-pressure chamber 48 contains a coil spring 55a which encircles the rod 49 and one end of said spring engages the follower 50. The parts so far described correspond functionally to parts of the speed control device 3.

10 The diaphragm operated rod 49 loosely extends through a central opening provided in a spring seat 55 and the outer end of said rod is connected by a pin 56 to a lever 57 corresponding functionally to lever 25 in Fig. 1 of the drawing. One end 15 of lever 57 is connected by a pin 58 to a link 59, the opposite end of which link is fulcrumed on a pin 60 secured in the casing of the structure. The opposite end of lever 57 is connected by pin 21 to link 28 which is connected by pin 29 to the fuel control lever 2.

20 The spring seat 55 is mounted to slide in an opening provided through the casing and is provided in the non-pressure chamber 48 with an enlarged cup-shaped portion 61 in which the adjacent end of control spring 55a is supported. The portion of spring seat 55 extending through the casing is provided with screw-threads upon which an adjusting nut 62 is mounted outside of the casing. This nut 62 is provided for engagement with the casing to limit movement of the spring seat 55 into the non-pressure chamber 48, while contact between the cup-shaped portion 61 and the interior wall of the non-pressure chamber is adapted to limit movement of the spring seat 55 in the opposite direction.

25 The speed and stop control device 45 further comprises a movable member preferably in the form of a flexible diaphragm 63 having at one side a pressure chamber 64 connected to the stop pipe 18 and having at the opposite side a non-pressure chamber 65. A follower 66 disposed in chamber 65 in contact with diaphragm 63 has a stem 67 loosely extending through an opening in the casing and connected by a pin 68 to one end of a lever 69. The lever 69 is fulcrumed intermediate 30 its ends on a pin 70 carried by an arm 71 projecting from the casing. The opposite end of lever 69 is bifurcated to straddle the diaphragm rod 49 and engages the outer end of spring seat 55.

35 In operation with the operator's control lever 35 in "stop" position opening pipe 8 to atmosphere and supplying fluid under pressure to pipe 18, diaphragm chamber 47 will be open to atmosphere while fluid under pressure will be supplied to diaphragm chamber 64. The pressure of fluid thus effective on diaphragm 63 will actuate said diaphragm to rock lever 69 in a clockwise direction which will move the spring seat 55 into the non-pressure chamber 48 to the position defined by contact between the nut 62 and the casing. This movement of spring seat 55 will change the position of the supported end of spring 55a which will exert sufficient pressure on the diaphragm follower 50 to deflect the diaphragm to the position shown in the drawing, and the resulting movement of rod 49 will rock the lever 57 to move the fuel control arm 2 to its "stop" position.

40 In order to move the fuel control arm out of its "stop" position to supply fuel to the engine to permit starting and running of the engine, the operator will move control lever 35 from its "stop" position to some position beyond "idle" in the direction of "full speed" in order to supply fluid at some degree of pressure in excess of atmospheric pressure to pipe 8 and thus to diaphragm chamber 47, while at the same time opening pipe 18 and

diaphragm chamber 64 to atmosphere. The resulting release of fluid under pressure from diaphragm chamber 64 will relieve the pressure of lever 69 on the spring seat 55, while the fluid pressure supplied to diaphragm chamber 47 will deflect the diaphragm 46 in the direction of the non-pressure chamber 48. Initially, this deflection of diaphragm 47 will merely act through spring 55a to move the spring seat 55 to the position in which the portion 61 contacts the casing and further deflection will then compress the spring 55a and the diaphragm will continue to deflect until the force of said spring counter-balances the force incident to pressure of fluid provided in chamber 47.

This deflection of diaphragm 46 will act through rod 49 to operate the lever 51 to pull the fuel control lever 2 out of its fuel cutoff or "stop" position and through its "idle" position to a position corresponding to the pressure of fluid provided in chamber 47, whereupon fuel will be supplied to the engine to permit starting and running thereof.

With this structure it should be noted that fuel will not be supplied to the engine upon movement of lever 35 from its "stop" position to its "idle" position since in "idle" position no fluid under pressure will be provided in diaphragm chamber 47 as required to actuate the diaphragm 46 for moving the fuel control arm 2 out of its fuel cutoff or "stop" position to a position for supplying fuel. In other words, it is necessary to provide a certain pressure of fluid in diaphragm chamber 47 upon release of fluid from chamber 64 to obtain fuel to provide for starting and running of the engine.

After the engine has been started and is running on fuel, the speed of the engine may be reduced to idling, if desired, by moving the operator's control lever 35 to its "idle" position which will effect a complete release of fluid under pressure from chamber 47. The spring 55a will then act to move the diaphragm 46 in the direction of the pressure chamber 47 and such movement transmitted through rod 49 and lever 51 will move the full control lever 2 in the direction of its "idle" position. This movement will continue until the fuel control arm obtains its "idle" position and will then cease, since in the corresponding position of diaphragm 46 and with the portion 61 on the spring seat 55 in contact with the casing, the spring 55a will have expanded to its free height and no longer exert force against the diaphragm.

Should the operator now desire to accelerate the engine, he will move lever 35 out of "idle" position in the direction of "fuel speed" position and thus provide fluid under pressure in diaphragm chamber 47. The diaphragm 46 will then deflect, against the opposing pressure of spring 55a, to a position corresponding to the pressure of fluid acting in chamber 47, and this movement will pull the fuel control lever 2 to a corresponding position to provide the desired increase in speed or power output of the engine. Adjustment of the lower 35 to any position between "idle" and "full speed" will provide a corresponding speed or degree of power output, as will be apparent.

If the operator desires to stop the engine he will move the lever 35 to its "stop" position for opening chamber 47 to the atmosphere and for supplying fluid under pressure to chamber 64 to deflect diaphragm 63 and thereby actuate lever 69 to push the spring seat 55 into the casing until the nut 62 engages the casing, and this movement

of said seat will act through spring 55a to move the diaphragm 46 to the position in which it is shown in the drawing. This movement of diaphragm 46 will in turn operate the lever 51 to push the fuel control arm 2 to its "stop" position for cutting off the supply of fuel to the engine whereupon the engine will stop.

As in the structure shown in Fig. 1 of the drawing, it will now be seen that with the structure shown in Fig. 2, a failure of the supply of fluid under pressure with the engine running can not result in stopping of the engine, but due to the loss of fluid under pressure from diaphragm chamber 47 can only result in operation of the structure to reduce the speed of the engine to idling. Stopping of the engine requires fluid under pressure. Thus in case of loss of fluid under pressure the engine will continue to operate and its speed may be controlled by conventional auxiliary or hand operated means usually associated with engines of this type.

Having now described my invention, what I claim as new and desire to secure by Letters Patent, is:

1. A fluid pressure control apparatus for selectively moving a control element to either a first position or a second position or out of said second position in a direction away from said first position comprising in combination, first and second relatively movable members in said casing means subject to pressure of fluid in, respectively, first and second chambers, control means selectively operable to effect a supply of fluid under pressure to either one of said chambers and to at the same time open the other one of said chambers to atmosphere to release fluid under pressure therefrom, said control means being also operable to open both of said chambers to atmosphere at the same time, mechanism operatively connecting said movable members to said control element, and spring means acting on said mechanism and operable, when both of said chambers are open to atmosphere, to effect operation of said mechanism to move said control element to said second position, said first movable member being operable in response to pressure of fluid supplied to said first chamber to effect operation of said mechanism to move said control element to said first position, and said second movable member being operable in response to pressure of fluid supplied to said second chamber to move said control element out of said second position in a direction away from said first position.

2. A fluid pressure control apparatus for selectively moving a control element to either a first position or to a second position or out of said second position in a direction away from said first position comprising in combination, casing means, first and second relatively movable members in said casing means subject to pressure of fluid in, respectively, first and second chambers in said casing means, a control spring in said casing means, acting on said first movable member in opposition to pressure of fluid in said first chamber, a regulating spring in said casing means acting on said second movable member in opposition to pressure of fluid in said second chamber, a lever having one end connected to said first movable member, means arranged to connect the opposite end of said lever to said control element, means operatively connecting said second movable member to said lever at a point intermediate the ends thereof, control means selectively operable to effect a supply of fluid under pressure to either one of said chambers and to at the same time open the other one of said chambers to atmos-

phere to release fluid under pressure therefrom, said control means being also operable to open both of said chambers to atmosphere at the same time, said first movable member being movable against said control spring, in response to supply of fluid under pressure to said first chamber, to actuate said lever to move said control element to said first position and being movable by said control spring upon opening said first chamber to atmosphere to actuate said lever to move said control element to said second position when said second chamber is also open to atmosphere, and said second movable member being adjustable against said regulating spring in response to fluid under pressure supplied to said second chamber to actuate said lever to adjust said control element out of said second position in a direction away from said first position.

3. A fluid pressure control apparatus for selectively moving a control element to different positions comprising in combination, casing means, first and second movable members in said casing means subject to pressure of fluid in, respectively, first and second chambers in said casing means, control means selectively operable to effect a supply of fluid under pressure to either one of said

chambers and at the same time to open the other one of said chambers to atmosphere to release fluid under pressure therefrom, said control means being also operable to open both of said chambers to atmosphere at the same time, a spring in said casing means acting on said second movable member in opposition to pressure of fluid in said second chamber, mechanism connecting said first member to said spring and operable by said first member in response to supply of fluid under pressure to said first chamber to effect operation of said spring to move said second member to one position, said first movable member being operable upon release of fluid under pressure from said first chamber to provide for said spring becoming ineffective on said second member in a different position of said second member, said second member being adjustable out of said different position in a direction away from said one position in response to supply of fluid under pressure to said second chamber, and mechanism connecting said second member to said control element and operable to adjust said control element in accordance with the position of said second member.

ROY R. STEVENS.
